Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing our new design;
FIG. 2 is a bottom view thereof;
FIG. 3 is a rear perspective view thereof;

FIG. 4 is a side view thereof;
FIG. 5 is an opposite side view thereof;
FIG. 6 is a front view thereof; and,

FIG. 7 is a rear view thereof.
The broken lines immediately adjacent to the shaded area define the bounds of the claimed design and form no part thereof. The broken lines within the shaded area represent features that form no part of the claimed design. The broken lines showing the remainder of the shoe represent unclaimed subject matter and form no part of the claimed design.
